HOSE REEL

Albert J. Granberg, Oakland, Calif., assignor of 7.99 per cent to Chesley M. Walter, 4.42 per cent each to Albert S. Kozman and Jacob E. Peregrine, 2.21 per cent each to Harvey May and Leslie E. Alley, 1.10 per cent to James E. Smith, and 22.13 per cent to Robert W. Lindsay

Original application February 12, 1945, Serial No. 577,567. Divided and this application October 27, 1945, Serial No. 624,961

1 Claim. (Cl. 299—78)

1

My invention relates to a system for the distribution of liquid through a hose, and more particularly to a hose reel component of such system.

This application is a division of my application for Retractable Hose Reel System, Ser. No. 577,567, filed February 12, 1945.

Among the objects of my invention are:

1. To provide a novel and improved hose reel;
2. To provide a novel and improved power retractile hose reel;
3. To provide a novel and improved hose reel adapted to work freely even when exposed to twisting stresses.

Additional objects of my invention will be brought out in the following description of a preferred embodiment of the same, taken in conjunction with the accompanying drawings whereinafter.

Figure 1 is a schematic diagram illustrating my improved retractile hose reel system, designed for application to a tank truck such as is customarily employed in the distribution of gasoline and the like to the storage tanks of service stations;

Figure 2 is a view, partly in section, illustrating an improved pump as an hydraulic generator and its manner of inclusion in the system;

Figure 3 is a view in section, taken in the plane 3—3 of Figure 2;

Figure 4 is an end elevational view of an improved hose reel embodied as a component in the system of Figure 1;

Figure 5 is a view in section, taken in the plane 5—5 of Figure 4;

Figure 6 is a view partly in section of a bypass control valve utilized in the system of Fig. 1.

As previously indicated, the invention has been illustrated as part of a system designed for use on a tank truck, and will be described as such, although its field of application is not limited to this specific use.

Referring to the drawings, a gasoline distributing pump 4, preferably of the type disclosed and claimed in my Patent No. 2,260,805 of October 28, 1941, is maintained in continuous drive connection from the truck engine (not shown) through a drive shaft 3 which is coupled to the pump shaft 5 through a universal coupling 7. This pump has its inlet or suction end connected to the tank (not shown) through an inlet pipe 9, and pumps the liquid through a discharge hose or pipe 10, which includes an air separator 11 and meter 13, to a discharge hose 15 carried on a suitable hose reel 17.

2

The air separator and meter could be similar to that described and claimed in Patent No. 2,272,170 of February 10, 1942, in which I am a joint inventor. This device and the hose reel are preferably installed in a conveniently accessible compartment 19 carried by the truck.

The hose reel 17 comprises a pair of end supports 21 and 23 interconnected by a hollow tubular shaft 25 fixed therein against rotation. On this hollow tube shaft there is rotatably mounted, as by means of spaced bearings 27 and 29, a drum 31 including a pair of end spiders 33 and 35 supporting a drum cylinder 37, at each end of which is affixed a hose confining rim or barrier 39 and 41, respectively.

Extending within the drum and formed integrally with one of the end spiders 33, is a housing 43 surrounding the fixed shaft 25 and sealed thereto at each end by means of rotary seals 45 and 47, respectively. The details of the rotary seal are incidental to the invention, but broadly comprise an assembly of sealing washers of different materials such as rubber, carbon and bronze, within the housing at each end thereof and maintained under continual compression against the ends of the housing 43, by a strong intermediate spring 49 of the compression type, surrounding the shaft 25 and exerting a strong outward pressure against each washer assembly.

End play or endwise movement of the reel drum 31 is avoided by abutting the housing 43 with a thrust collar 51 which surrounds the shaft 25 and is affixed thereto by means of a plurality of radially disposed setscrews 53. This thrust collar is enclosed by an end cap 55 affixed to the end of the housing 43 and formed to provide for the inclusion of a dust seal 57.

At a location in the tubular shaft 25 within that portion which is encircled by the housing 43, the shaft is formed with one or more openings 59 to provide communication between the tubular shaft and the interior of the housing.

Adjacent that end of the housing 43 adjacent the spider 33, the housing is formed with a flanged opening 61 for attachment thereto of a lead-off hose connection 63 extending substantially radially through the drum and terminating in a bend 65 at the surface of the drum. The hose 15 to be carried on the reel, has one end connected to this lead-off connection. The lead-off connection may be directed in either direction circumferentially of the drum, depending upon the direction in which the hose is to be wound on the reel.

A reel constructed as described, is adapted to receive fluid by way of the hollow shaft 25, from which it will flow into the housing 43, and from there will be directed through the lead-off hose connection 63 to the hose itself.

In adapting the reel for the introduction of fluid into the tubular shaft, the shaft is preferably provided with a screw-threaded flange 67 at each end, and is closed off at one end by a flange plate 69 bolted to the flange with the customary leak-proof gasket 71 between the two. That end of the shaft into which the liquid is to be pumped, is coupled to the hose or pipe 10 coming from the pump 1.

In a reel of the type described, the drum 31 is always freely rotatable on the fixed shaft 25 and, therefore, will not bind on the shaft when the end supports are subject to twisting as is apt to occur in a truck installation due to weaving or road conditions. Similarly, the construction illustrated avoids the use of swivel connections, and particularly is this of importance where such connections are incorporated in a mobile installation as in a tank truck.

In preparing for the dispensing of gasoline from the truck tank, the operator unwinds sufficient of the hose from the reel to reach the customer's storage tank. Following the discharge of the proper amount of gasoline into the customer's storage tank, the hose must of necessity be rewound on the reel. A feature of the present invention resides in an hydraulic system whereby this may be readily accomplished by the operator.

Toward this end, I affix a ring gear 73 to one of the end spiders 33 of the reel. On the adjacent end support 21 for the reel, I mount an hydraulic motor 75 in drive connection with the ring gear 73 as by a pinion 74 meshing with gear 73. A chain drive could be substituted if desired. The hydraulic motor 75 is operated from an hydraulic generator 77 to which it is connected by a pipe system 79 including a pipe connection 81 between the outlet of said generator and the inlet of said motor, and a pipe connection between the outlet of said motor and the inlet of said generator.

A small reservoir 85 connected in the latter pipe connection 83 which constitutes the return line of the pipe system, serves to maintain a full supply of fluid in the hydraulic system, and at the same time functions to accommodate changes in the capacity of the system due to expansion or contraction thereof.

The hydraulic generator 77 is bolted to and supported by a gland 87 associated with the main pump 1, and is driven from the main pump shaft 5 by a gear train 89 including a pinion 91 keyed to the main pump shaft and meshing with a gear 93 keyed to the shaft 94 of the hydraulic generator 77. The gear train 89 is enclosed in a casing involving a plate 95 affixed to the pump gland 87 and hydraulic generator casing as by machine screws, and an enclosing cover 97.

The packing gland 87, it is noted, is bolted to the main pump 1 with its axis coinciding with the pump shaft axis, and consequently the gland may be rotatably adjusted to as many positions as there are bolts holding the gland to the pump.

The significance of this lies in the fact that the hydraulic generator 77 being supported by the gland, is therefore likewise capable of being shifted to any one of a number of positions about the pump shaft 5 as an axis, and such po-

sitional adjustment will likewise be permitted by the gear train 89. The ability to so shift the position of the hydraulic generator is of importance in a truck or any other type of installation where space is a material factor to be considered.

Inasmuch as the hydraulic generator is directly connected to the shaft of the main pump 1, it will be in continuous operation so long as the truck engine is running, and it is necessary that the engine run so long as it is necessary to operate the truck or to pump gasoline from the truck tank. On the other hand, it is only infrequently that one finds it necessary to rewind the hose on the reel.

Consequently, to permit idling of the reel during such long intervening periods when rewinding is not necessary, I provide a normally short circuiting valve 99 (Fig. 1) between the two pipe connections 81 and 83 of the hydraulic system, and preferably locate such valve adjacent the hydraulic motor 75 where it will be within convenient reach and control of an operator, as he guides the hose onto the reel during rewinding. Such short circuiting valve may be of the type illustrated in Fig. 6 which has a passage 100 therethrough capable of being closed in varying degrees by a gate 101 which is biased to an open position by a biasing spring 103, bearing against a handle 105 which is capable of being manually operated to adjust the valve opening from its fully open position to any degree of closing. In its normal fully open position, the valve serves to by-pass around the hydraulic motor 75, the operating fluid in the hydraulic system, and thus the operating fluid has no operating effect on the hydraulic motor, and the hose reel 17 will accordingly idle.

However, as the valve gate is urged toward its closing position, more and more of the operating fluid will be diverted to the hydraulic motor 75 and cause the same to respond at various speeds, depending on the degree of closing of the valve. Thus the operator has positive control and can govern the speed of rewind to suit his desires.

Not infrequently, however, due to carelessness of the operator, or in spite of care exercised by him, the hose may tangle or a kink may develop therein, and the resulting increase in load placed upon the hydraulic motor, could create pressure in the system sufficient to damage the reel or burst the hose.

As a precaution against this, I provide a poppet or check valve 107 in a connection between the two pipe lines 81 and 83 of the system and adjust such valve to open at a maximum permissible pressure in the system. This valve accordingly renders the system substantially fool-proof against damage, and eliminates the necessity of an operator to use extreme caution in the utilization of the system.

The hydraulic generator 77 and hydraulic motor 75 are, from the viewpoint of economy, preferably of identical construction, and with this purpose in mind, I have developed a pump capable of use either as the hydraulic generator or as the hydraulic motor of the system.

Such pump comprises a casing 109 having an internal cylindrical chamber 111 defined by a pair of spaced side walls 113 and 115 and a connecting wall 117. One of the side walls 115 is formed internally with a blade guide track about the axis of said chamber in the form of a circular channel 119 having its center of curvature 121 on the

axis of the chamber. This channel is adapted to slidably receive a plurality of arcuate segments 123 which function as anchors for the pump blades 125, to be subsequently described.

The side 113 is formed with an axial end pocket 127 to receive a rotary seal 129 and a shaft bearing 131 of the ball bearing type. The pump shaft 94 passes through this rotary seal and bearing, and terminates in a bearing 133 in the opposite side wall 115, the bearings being in alignment on an axis parallel to the axis of the chamber 111 but eccentrically disposed with respect thereto.

The shaft 94 carries a rotor 135 within the chamber, such rotor including a peripheral rim 137 on a plurality of spokes 139 equal in number to the number of blades 125 to be employed in the pump or the number of segments 123 for anchoring the blades. The peripheral rim 137 of the rotor extends the axial length of the chamber, and is of a diameter to tangentially approach the cylindrical surface of the chamber at its nearest point.

Each of the rotor spokes 139 is provided with a deep radial slot 141 extending through the rim of the rotor, to slidably receive one of the blades 125 of the pump, such blade being pivotally anchored to one of the slideable segments 123 as by a pivot 143 affixed to an edge of the blade and inserted into a pivot hole formed in the segment.

As can be seen from Figure 2, the rotor spokes are of reduced thickness, thereby permitting liquid flow from one portion of the circular channel 119 to another. The significance of this lies in the fact that the segments 123 in their cyclic movement around the pump shaft alternately approach and recede from each other, thus alternately expelling and drawing in liquid into the channel. In as much as reverse conditions exist at diametrically opposite points of the channel, an interchange of liquid is always demanded during operation of the pump. As indicated, the rotor spokes permit of such interchange.

Each blade is of a length to approach the cylindrical surface of the chamber with a minimum of clearance with respect thereto. Inasmuch as the circular channel is concentric with the chamber, all blades will be of the same length.

A passage to the pump chamber is provided to one side of the tangential contact of the rotor in the form of a channel 145 formed in the connecting wall 117 and having communication with the exterior of the pump through a threaded opening 147. A similar passage 149 having outside communication through a corresponding threaded opening 151, is provided to the other side of such tangential contact. Either passage may serve as the inlet or discharge passage of the pump, depending upon the direction of rotation of the rotor desired. For convenience of disclosure, the passage 145 will be considered the inlet passage. Each blade in turning, effects a cut-off at the end 153 of the inlet passage 145 and permits of initial discharge from a pocket when such blade reaches the corresponding point 155 of the discharge passage.

It is important that the maximum spread or developed angle between blades should substantially span the arc between the end of the inlet passage and the beginning of the discharge passage as shown in the drawings. The importance of this can best be seen if unfavorable conditions are assumed. Thus, should maximum spread be reached at an angle which does not span the arc in question, the subsequent reduction in the spread angle, which operation of the pump would

call for, could not be effected against the incompressible liquid between the blades and something must give way. This means bursting of the pump.

Were the angle of spread greater than the arc in question, a vacuum will develop between the blades and cause considerable noise comparable to water hammer in steam pipes.

The aforementioned relationship can best be obtained by proper determination of the respective lengths of the inlet passage and discharge passage.

In conventional pumps operating on this general principle, the cylindrical wall of the chamber is employed as a guide for the blades and consequently each blade must be in constant frictional engagement with the surface of the chamber, resulting in wear of the blades and oftentimes in the blades binding and causing damage to the pump. By anchoring the blades in arcuate segments as described, a minimum clearance may be maintained between the blades and the cylindrical wall of the chamber whereby the blades are not exposed to wear and under no conditions could they possibly bind.

In view of the eccentric disposal of the rotor, the blades do not maintain radial positions in the pump chamber as they are moved around by the rotor, but are forced to swing slightly to either side of such radial positions. Under the circumstances, and to assure maintenance of minimum clearance between the blades and the cylindrical surface of the pump chamber, the blades are of a thickness such that in positions of maximum swing, an extreme edge of the blade will offer the proper minimum clearance.

Another feature of the pump lies in its symmetrical construction, with both openings 147 and 151 adjacent each other. This not only permits of interchangeability of connections to the pump for determination of its direction of rotation, but when supported in the position illustrated in Figure 3, the pump will retain prime regardless of the directional rotation thereof.

From the above description of a preferred embodiment of my system and components thereof as adapted for installation on a tank truck, it will be apparent that the same fulfills all the objects of my invention as previously set forth, and while I have described one embodiment of my invention in considerable detail, the same is subject to alteration and modification, without departing from the fundamental concepts thereof.

I accordingly do not desire to be limited in my protection to the specific details illustrated and described, except as may be necessitated by the appended claim.

I claim:

60 A hose reel for mounting on a truck, comprising a pair of parallel spaced end supports, a hollow shaft fixedly supported on said end supports and having one end closed; a reel drum rotatably mounted on said shaft, said reel drum including a pair of end spiders, a drum cylinder carried by said spiders and surrounding said shaft, and a hose confining rim affixed to each of said spiders adjacent the ends of said drum cylinder; a housing extending inwardly to an intermediate point within said drum cylinder from one of said spiders and having communication with the interior of said shaft, a lead-off hose connection extending from said housing to the surface of said drum cylinder adjacent one of said hose confining rims; and a power drive connection to said reel, includ-

ing a gear on one of said spiders for engagement by a drive pinion.

ALBERT J. GRANBERG.
